UNITED STATES PATENT OFFICE.

WILLIAM H. KEYSER, OF WILLS POINT, TEXAS.

BUILDING CONSTRUCTION.

No. 853,802.

Specification of Letters Patent.

Patented May 14, 1907.

Application filed May 23, 1905. Renewed October 20, 1906. Serial No. 339,365.

To all whom it may concern:

Be it known that I, WILLIAM H. KEYSER, a citizen of the United States, residing at Wills Point, in the county of Van Zandt and State 5 of Texas, have invented new and useful Improvements in Building Construction, of which the following is a specification.

This invention relates to certain new and useful improvements in building construction, 10 and particularly to the construction of metallic beams, columns, girders, joists, studs, etc., formed of plates and adapted to be embedded in concrete, one object of the invention being to provide an improved construction of plate having perforations for the passage of the cement or concrete through it, whereby the embedded plate is adapted to be more firmly and rigidly bound in the concrete in such manner as to utilize its full tensile, 15 compressive strength.

Another object of the invention is to provide plates in which the perforations are so formed as to not materially weaken the plate while affording a more effective bonding of the plates by the concrete, the openings further being so constructed as to provide embedding projections which materially strengthen the connection.

Still another object is to provide simple and 30 effective means for joining the plates or elements of a girder or joist to form an arch or truss in the concrete; also to provide a simple and secure connection for supporting joists and studs from girders.

With this and other objects in view, the 35 invention consists of the features of construction, combination and arrangements of parts hereinafter fully described, reference being had to the accompanying drawings, in 40 which:

Figure 1 is a perspective view showing a column, girder and joist constructed in accordance with the invention; Fig. 2 is a fragmentary side elevation of a column and girder; Fig. 3 is a sectional view through the stirrup and contiguous portions of the girder and joist; Fig. 4 is a vertical cross section through the girder as completed and embedded in the concrete; Fig. 5 is a horizontal section of the 45 same; Fig. 6 is a plan view showing the mode of connecting girders to a column and also the arrangement of the transverse truss plates; Fig. 7 is a detail view of the stirrup; Fig. 8 is a section on line 8—8 of Fig. 9; and Fig. 9 is a plan view of a portion of the girder.

Referring now more particularly to the

drawings, the letter A designates a column, B a girder, and C a joist, constructed of elements made in accordance with my invention.

In structural steel works, beams, columns, girders, joists, studs and like portions of a structure are formed of plates, generally rolled steel plates, which are joined to form a part or element, the several different parts or 65 elements of the building structure being riveted or otherwise joined together. These elements are generally embedded in cement or concrete to securely tie them together and form a rigid, strong and durable mass, where- 70 by the metallic parts are effectually protected from atmospheric influences and are adapted to be employed to form a wall, ceiling or floor structure which is fire proof and of maximum strength to resist the strains to 75 which the parts of large and heavy buildings are subjected. One object of my invention is to provide means for more securely and rigidly bonding the parts and positively fastening them to the concrete in which they 80 are embedded so that they can not possibly shift and cause disintegration of the concrete or cement mass and throw objectionable strain upon the coöperating elements of the building structure. To this end, I provide 85 each plate or element 1 with a plurality of apertures 2 through which the cement may pass when the plate or element is embedded therein, the portions of the cement passing through the apertures constituting bonds 90 which rigidly connect the portions of concrete or cement lying upon opposite sides of the plate and thereby securely tie them together, this construction causing the plate to be rigidly held against shifting so that its 95 full strength may be utilized without throwing strain upon connecting parts. In order to secure the best results, the holes or apertures 2 are so formed and arranged as to prevent weakening of the plate to any material extent, for this purpose the holes are arranged in longitudinal transverse rows and graduated in size, the holes of the intermediate longitudinal row being largest, those of the outer row lying nearest the edges of the plate 100 next in size, and those between the central outer longitudinal rows smaller than the openings in either of the first named rows. By this construction the larger holes or openings formed in the plate are widely separated, while intermediate openings are pro- 105 vided between them in order that the entire 110

surface of the plate may be bonded in the cement. Further the intermediate rows of openings are arranged out of alinement with the outer larger rows of the openings, so that while the larger openings lie in alinement transversely and form both transverse and longitudinal rows, the intermediate openings will lie on lines between the transverse rows of the larger openings, thus providing in effect a staggered relation of the openings which causes them to be disposed in such manner as to effect the tying or bonding of the plate in the cement in the most efficient way and without unduly weakening the plate or impairing its tensile, tensile and compressive strength. These apertures also permit of the use of vertically disposed bracing plates between the elements of a column or other vertically disposed structural part in order to increase the strength thereof, as the connecting portions of cement passing through the openings will prevent the plate from shifting and hold it rigidly in a perpendicular position, thus allowing its full tensile, tensile and compressive strength to be attained and utilized.

Each opening 2 is formed by the action of a suitable die or punch, and in the operation of forming it the metal displaced to produce the same is laterally deflected to project from opposite sides of the plate and form opposite ragged edges or series of projections 4, which are also embedded in the concrete in the process of building a structural part and adds greatly to the bonding and holding action, the projections supplementing the action of the portions of cement projecting through the holes to prevent movement or shifting of the plate in its bed of concrete in any direction. In the successive rows of openings, the ragged edges or projections 4 may be alternately displaced upon opposite sides of the plate, that is to say, the projection of one opening will extend from one side of the plate, while the projection of the next adjacent opening will extend from the opposite side of the plate, and so on throughout the series of holes, thus arranging the said projections so that the holding action on both sides of the plate will be equalized throughout the length thereof. In fact either construction will be such that the projections will hold the plate so firmly that the latter cannot shift without being broken under the strain.

In the construction of girders and joists, I preferably employ a series of bracing or truss plates 5 between the plates or elements 1, these brace or truss plates 5 being formed with perforations 6 similar to the perforations 2 for the purpose of bonding or holding them fast in the bed of cement. The plates 5 are secured in position by means of bolts 7 or other suitable fastenings attached to the plates 1 and are set at an angle to the verti-

cal, as clearly shown in Figs. 2 and 6, said plates being, in other words, arranged obliquely or substantially so to the longitudinal axis of the plates, so as to present broad upper and lower faces at an angle to the portions of cement above and below, so that when embedded they will practically form a series of arches or trusses in the concrete, thus rigidly tying or bonding the plates 1 and forming a structure which is absolutely rigid in a solid mass and which will effectually prevent independent play of the parts to a sufficient extent to cause wear upon the connecting bolts or rivets or disintegration of the cement or concrete in which the elements are embedded.

The ordinary mode of connecting the elements of a structure together may be employed except in the case of connecting a joist from a beam or girder, in which instance I preferably employ a stirrup 8 of the form shown in detail in Fig. 7. This stirrup is adapted to receive and support the contiguous end of the joist, and is provided at its upper edge with a plurality of hooks 9 adapted to engage the upper edge of one of the plates or elements of the beam or girder to support the joist therefrom. The stirrup may be bolted or riveted to the parts which it connects or it may be left loose, as it will be securely bound in position by the bed of concrete. This mode of connection is simple, cheap and effective.

It will be understood, of course, that in the construction of both horizontal and vertical structural elements one or more of the perforated plates may be disposed between the plates of the elements in order to effect a more rigid, strong and durable connection, and that in the adaptation of the invention to either rectangular or circular columns a number of apertured plates may be disposed vertically therein in such manner as to more securely tie and bond the parts at the opposite sides thereof, thus giving a strong and durable axial support in which the parts will be bound together in a solid mass. By this mode of using interior perforated plates a continuous construction either in columns or walls is effected. It is readily understood that concrete construction should not stop after being commenced, and my construction permits a continuous construction to be more effectively carried on, but in the event of a delay in operation for a short time perforated steel plates, either vertical or horizontal, may be inserted at such points as may become necessary to fully bond the same as though the work were continued without delay.

From the foregoing description, taken in connection with the accompanying drawings, the construction and mode of operation of the invention will be understood without a further extended description.

Changes in the form, proportions and mi-

nor details of construction may be made within the scope of the invention without departing from the spirit or sacrificing any of the advantages thereof.

5 Having thus described the invention, what I claim as new, is:—

1. A structural element for buildings comprising spaced perforated plates and intermediate angularly arranged perforated bracing plates.

10 2. A structural element for buildings comprising spaced perforated plates, an intermediate perforated plate, and a body of cement in which the plates are embedded, the portions of the cement between the plates being joined by integral portions thereof projecting through the apertures in the plates.

15 3. A structural element for buildings com-

prising spaced parallel plates, angularly arranged bracing plates between said parallel plates, and bolts passing through said bracing plates and tying the same to the parallel plates.

4. A structural element for buildings comprising spaced parallel plates, series of angularly arranged bracing plates between said parallel plates, the bracing plates of one series being arranged on lines between the bracing plates of the other series, and fastenings tying the bracing plates to the parallel plates.

In testimony whereof, I affix my signature in presence of two witnesses.

WILLIAM H. KEYSER.
